(57) **CLAIM**

The ornamental design for an oral waterjet as shown and described.

DESCRIPTION

FIG. 1 is a front, right and top perspective view of a first embodiment of an oral waterjet, showing our design.

FIG. 2 is a rear, left and bottom perspective view of the oral waterjet in the FIG. 1.

FIG. 3 is a front elevation view of the oral waterjet in the FIG. 1.

FIG. 4 is a rear elevation view of the oral waterjet in the FIG. 1.

FIG. 5 is a left side elevation view of the oral waterjet in the FIG. 1.

FIG. 6 is a right side elevation view of the oral waterjet in the FIG. 1.

FIG. 7 is a top plan view of the oral waterjet in the FIG. 1.

FIG. 8 is a bottom plan view of the oral waterjet in the FIG. 1.

FIG. 9 is an exploded view of the oral waterjet in the FIG. 1

FIG. 10 is a front, right and top perspective view of a second embodiment of an oral waterjet.

FIG. 11 is a rear, left and bottom perspective view of the oral waterjet in the FIG. 10.

FIG. 12 is a front elevation view of the oral waterjet in the FIG. 10.

FIG. 13 is a rear elevation view of the oral waterjet in the FIG. 10.

FIG. 14 is a left side elevation view of the oral waterjet in the FIG. 10.

FIG. 15 is a right side elevation view of the oral waterjet in the FIG. 10.

FIG. 16 is a top plan view of the oral waterjet in the FIG. 10.

FIG. 17 is a bottom plan view of the oral waterjet in the FIG. 10.

FIG. 18 is an exploded view of the oral waterjet in the FIG. 10.

(Continued)

FIG. 19 is a front, right and top perspective view of a third embodiment of an oral waterjet.

FIG. 20 is a rear, left and bottom perspective view of the oral waterjet in the FIG. 19.

FIG. 21 is a front elevation view of the oral waterjet in the FIG. 19.

FIG. 22 is a rear elevation view of the oral waterjet in the FIG. 19.

FIG. 23 is a left side elevation view of the oral waterjet in the FIG. 19.

FIG. 24 is a right side elevation view of the oral waterjet in the FIG. 19.

FIG. 25 is a top plan view of the oral waterjet in the FIG. 19.

FIG. 26 is a bottom plan view of the oral waterjet in the FIG. 19.

FIG. 27 is an exploded view of the oral waterjet in the FIG. 19.

FIG. 28 is a front, right and top perspective view of a fourth embodiment of an oral waterjet.

FIG. 29 is a rear, left and bottom perspective view of the oral waterjet in the FIG. 28.

FIG. 30 is a front elevation view of the oral waterjet in the FIG. 28.

FIG. 31 is a rear elevation view of the oral waterjet in the FIG. 28.

FIG. 32 is a left side elevation view of the oral waterjet in the FIG. 28.

FIG. 33 is a right side elevation view of the oral waterjet in the FIG. 28.

FIG. 34 is a top plan view of the oral waterjet in the FIG. 28.

FIG. 35 is a bottom plan view of the oral waterjet in the FIG. 28; and,

FIG. 36 is an exploded view of the oral waterjet in the FIG. 28.

The dashed broken lines depict portions of the oral waterjet that form no part of the claimed design.
